UNITED STATES PATENT OFFICE.

ARTHUR A. BYERLEIN, OF TOLEDO, OHIO, ASSIGNOR TO THE TOLEDO MACHINE & TOOL COMPANY, OF TOLEDO, OHIO, A CORPORATION OF OHIO.

DRAWING PRESS.

Application filed November 3, 1920. Serial No. 421,491.

To all whom it may concern:

Be it known that I, ARTHUR A. BYERLEIN, a citizen of the United States, and a resident of Toledo, in the county of Lucas and State of Ohio, have made an Invention Appertaining to Drawing Presses; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to drawing presses, and particularly to those of the type in which the blank holder precedes the work shaping member in its engagement of the blank and then dwells or pauses and firmly 20 holds the blank during the shaping operation. The invention also relates to the type of machine shown and described in United States Letters Patent No. 1,176,897 of March 28, 1916.

25 The object of my invention is to provide a simple and efficient operating means for the blank holding and shaping members whereby to enhance the practicability and commercial value of machines of this class.

30 The invention is fully described in the following specification, and while, in its broader aspect, it is capable of embodiment in numerous forms, a preferred embodiment thereof is illustrated in the accompanying drawings, in which—

35 Figure 1 is a front elevation of a machine embodying the invention, with parts broken away, and with the die members removed and the blank holding and shaping members in elevated position. Fig. 2 is a central vertical section thereof with the lower portion in full and with the die members in position. Fig. 3 is an enlarged section on the line 3—3 in Fig. 2. Fig. 4 is a fragmentary cross-sectional view of the machine, with the blank holder and shaping members at the limit of their downward strokes, and Fig. 5 is an enlarged sectional detail of a part of the machine.

40 Referring to the drawings, 1 designates the base of the machine, forming on its top the bed plate 2, having a die 3, in the present instance of male form, mounted thereon. A stripper member 4 is mounted in a recess in the die, and after each work shap-

ing operation is elevated by suitable mechanism to strip a shaped work piece from the die. The stripper operating mechanism forms no part of the present invention and need not therefore be described.

45 The machine frame has the customary side uprights 5 and connecting top cross-piece 6, the uprights 5 forming guides for directing the vertical reciprocatory travel of the blank shaping member 7, carrying the shaping die 8 on its bottom for cooperating with the die 3 in the shaping operation. The member 7 is of hollow form and has the blank holder plunger 9 mounted for reciprocatory movements therein. This plunger 50 has pins 10 projecting downward through the bottom of the shaping member 7 for free reciprocatory movements relative thereto and carrying a blank holding pad 11 at their lower ends within a recess in the upper 55 die 8 for coacting with the central elevated portion of the male die 3 to hold a blank during a shaping operation.

60 The customary crank shaft 12 is mounted in the upper portion of the frame and so has cranks 13, 13 at opposite ends thereof which are connected by connecting rods or pitmans 14 with the respective ends of the shaping member 7, whereby the shaping member has reciprocatory movements imparted thereto from a turning of the cranks.

65 The blank-holder 9 is provided at its top above each end thereof and without the top of the shaping member 7 with a cross-bar 15, which is connected with the plunger by rods 16 and is provided at its ends with vertical guide rods 17, which project at their ends loosely through guide bosses 18 and 19 provided respectively on the sides of the member 7 and of the frame top 6. Each 70 cross-bar 15 carries a roller 20, which is acted on during a predetermined portion of a revolution of the crank shaft by a registering cam 21 on such shaft to effect first a lowering of the blank holder 9 at a predetermined speed with respect to the lowering of the shaping member 7, then to cause the blank holder to dwell during the blank shaping operation, and then to permit the blank holder to raise to its normal position. The 75 raising or return of the blank holder to its normal position is effected by the engagement of adjustable studs 22 on the top of the member 7 with registering spring bumpers 23 on the cross-bars 15 when the mem-

ber 7 has raised a predetermined extent from its lowered position.

The desired relative adjustment of the shaping member 7 and blank holder 9 is obtained by a shortening or lengthening of the members 16 between the plunger 9 and cross-bars 15, which is effected by a turning of the members 16 to thread them into or out of one or the other of the members which they connect. A uniform adjustment of the connecting members 16 is obtained by providing each member with a worm-wheel 24 in mesh with driving worms on a common worm shaft 25, as is well understood in the art.

It is evident, in the operation of a machine equipped with my improvement, that the blank-holder plunger 9 and shaping member 7 lower together upon a turning of the crank shaft 12 until the blank holder pad rests on the work and that the cams 21 then act to cause the blank holder to dwell during the remainder of the downward blank shaping movement of the member 7 and for a portion of its upward stroke due to the prolonged engagement of the neutral portion *a* of the cams with the rollers 20. When the shaping operation is completed by reason of the member 7 completing its downward stroke said member is positively raised to its elevated position and when it has raised a predetermined extent the thrust studs 22 coat with the spring bumpers 23 and raise the blank holding plunger 9 therewith.

It is evident that during the shaping operation the central portion of the blank is firmly held flat against the registering portion of the lower die and against warping or buckling while the edges thereof are being shaped by the cooperative action of the dies. This is an especially important feature in presses of this character, for with the types of presses in which the blank is gripped and held stationary during the

shaping operation, the center of the blank, in being driven into the cavity of the female die, is more or less buckled and warped and in some cases to such an extent as to prevent the formation of perfect work.

I wish it understood that my invention is not limited to any specific construction, arrangement, or form of the parts, as it may be changed and modified in numerous respects without departing from the spirit of the claim.

Having thus described my invention, what I claim as new, and desire to secure by Letters Patent, is,—

In a drawing press, a frame, a hollow vertically reciprocable shaping plunger carried by the frame, a vertically reciprocable blank holding plunger in the shaping plunger, vertically aligned guides carried by the frame and the opposite sides of the shaping plunger, cross bars spaced above the upper end of the blank holding plunger, means in said space for adjustably connecting the cross bars to the upper end of the blank holding plunger, guide rods projecting upwardly and downwardly from and secured intermediate their ends to the cross-bars and received in said guides, adjustable studs in the space between the cross bars and the blank holding plunger, extending upwardly from the upper end of the shaping plunger, spring bumpers carried by the cross bars and in registry with said studs and also arranged in the space between the cross bars and the blank holding plunger, a crank shaft carried by the frame and connected to the shaping plunger to actuate the latter, and cams on the crank shaft located in close relation to the tops of the cross bars and in the space between the upper ends of the guide rods to actuate the latter and thereby the blank holding plunger.

In testimony whereof I have hereunto signed my name to this specification.

ARTHUR A. BYERLEIN.
